UNITED STATES PATENT OFFICE.

JOHN F. ELLIOTT, OF ALLERTON, IOWA.

TRACK LINER.

Application filed May 20, 1924. Serial No. 714,658.

To all whom it may concern:

Be it known that I, JOHN F. ELLIOTT, a citizen of the United States, residing at Allerton, in the county of Wayne and State 5 of Iowa, have invented certain new and useful Improvements in Track Liners, of which the following is a specification.

This invention relates to an improved track liner and seeks, among other objects, 10 to provide a device of this character which will be quick in action while, at the same time, ample leverage will be present to accomplish the work.

The invention seeks, as a further object, 15 to provide a device which may be readily employed not only for raising or lowering a track but also for shifting the track laterally.

And the invention seeks, as a still further 20 object, to provide a device wherein excess weight will be eliminated so that the device may be readily handled in practical use while, at the same time, the device will be strong and durable.

Other and incidental objects will appear 25 hereinafter.

In the drawings:

Figure 1 is a perspective view of my improved track liner,

Figure 2 is a side elevation of the device,

Figure 3 is a sectional view taken medially through the device,

Figure 4 is a sectional view showing a slight modification of the invention, and

Figure 5 is a transverse sectional view 35 on the line 5—5 of Figure 4, looking in the direction of the arrows.

In carrying the invention into effect, I employ a base plate 10 on which is formed 40 or otherwise secured a plurality of spurs 11 and rising from the base plate medially thereof is a longitudinally directed bracket plate 12 having a concave forward edge. At the forward end of the plate 12, the

base plate is provided with a notch 13 and, 45 as will be observed, the portions of the base plate at opposite sides of the notch are beveled, as indicated at 14. Pivoted upon the forward end of the plate 12 at its upper

extremity is a lifting arm 15 provided at 50 its upper end with ears 16 straddling said plate and extending through the ears and through the plate is a pivot pin 17. Formed on the arm 15 at its lower end is a for- 55 wardly directed downwardly inclined toe 19 which may be provided with teeth or

otherwise roughened and, as will be observed, the arm 15 is of such length that when swung downwardly, the toe 19 will be received in the notch 13 of the base plate 60 10. Preferably, the rear face of the arm is curved to fit the curved forward edge of the bracket plate so that the arm may seat flat thereagainst.

The plate 12 is substantially triangular in 65 general contour to incline downwardly toward its rear end and straddling said plate is forked lever 20. Extending through the forks of said lever and through the plate 12 is a pivot pin 21 swingingly mounting the 70 lever and, as brought out in Figure 3 of the drawings, the plate is preferably equipped with spaced bushings 22 to selectively receive said pin so that the fulcrum of the lever may thus be shifted. For a 75 like reason, the forked arms of the lever are provided with spaced openings 23 to selectively receive the pin and, preferably, these openings are also bushed. At its upper end, the lever is formed with a squared 80 socket to removably receive a suitable handle 24 and formed on the fork arms of the lever at their lower ends are yokes 25. Extending between the yokes and the arm 15 at opposite sides thereof are links 26 pivotally connected with the yokes and with the arm by pivot pins 27 and, preferably, the yokes, links and arm are bushed to receive the pins. Likewise, the ears 16 of the 85 arm as well as the plate 12 are preferably 90 bushed to accommodate the pin 17. Undue wear upon the parts will thus be eliminated and, as will now be seen, after the device has been positioned adjacent a track, the lever 95 15 may be operated for swinging the arm 20 upwardly to engage the toe 19 of the arm beneath the adjacent track rail when by 100 swinging the lever downwardly the track may be tilted upwardly or lifted. In like manner, the device may be employed for crowding the track laterally.

In Figures 4 and 5 of the drawings, I have illustrated a slight modification of the invention wherein I employ a base plate 28 having spurs 29 and formed in the plate at 105 its forward end is a medial notch 30. Rising from the base plate at opposite sides of said notch are bracket plates 31 in which is pivoted a lifting arm 32 similar to the arm 15 of the prior embodiment of the invention and provided at its lower end with a downwardly inclined toe 33 normally ac- 110

commodated in the notch 30. Pivoted between the plates 31 in the rear of the arm is a lever 34 provided at its upper end with a squared socket 35 to removably receive a handle and connecting the lower end of the lever with the lower end portion of the arm 32 is a link 36. Thus, the lever may be swung for operating the lifting arm and, as will be observed, the plates 31 are provided with spaced openings to selectively receive the pivot pin of the lever while the lever is itself also provided with spaced openings to receive the pin so that the fulcrum point of the lever may be shifted.

Having thus described the invention, what I claim is:

1. In a track liner, the combination of a base plate having a bracket plate rising therefrom, a hand lever pivoted at a point between its ends upon the bracket plate, a lifting arm pivoted at its upper end upon the bracket plate forwardly of the pivot point of the lever, and means secured to the forward end portion of the lever and to the lower end portion of the arm connecting the lever and arm to swing in unison and movable to closely approach an alined position with respect to the lever as the lower end of the arm is swung upwardly.
2. In a track liner, the combination of a base plate having a bracket plate rising

therefrom, a hand lever having a fork straddling the bracket plate and pivoted at a point between its ends thereon, a lifting arm pivoted at its upper end upon said bracket plate forwardly of the pivot point of the lever, and links secured to the free ends of said fork and to the lower end portion of the arm connecting the lever and arm to swing in unison and movable to closely approach an alined position with respect to the lever as the lower end of the arm is swung upwardly.

3. In a track liner, the combination of a base plate provided at its forward end with a notch and having a bracket plate rising therefrom to overhang said notch, a hand lever pivoted at a point between its ends upon the bracket plate, a lifting arm pivoted at its upper end upon the bracket plate above the notch and provided at its lower end with a toe normally accommodated in the notch, and means secured to the forward end portion of the lever and to the lower end portion of the arm connecting the lever and arm to swing in unison and movable to closely approach an alined position with respect to the lever as the lower end of the arm is swung upwardly.

In testimony whereof I affix my signature.

JOHN F. ELLIOTT. [L. s.]
